ATTORNEY:

UNITED STATES PATENT OFFICE.

GEORGE C. LINDSEY, OF LOS ANGELES, CALIFORNIA, ASSIGNOR OF NINE THIRTY-SECONDS TO ROBERT TURNER, SEVEN THIRTY-SECONDS TO MICHAEL GOZZO, ONE-EIGHTH TO DON EMINER, AND SIX THIRTY-SECONDS TO VICTOR P. HENDRICK.

OPERATING UNIT FOR SOUND-AMPLIFYING DEVICES.

Application filed February 8, 1926. Serial No. 86,780.

This invention is an operating unit for a sound reproducing and amplifying device which is particularly adapted for use in radio reception, and it is the object of the 5 invention to provide a simple mounting and adjustment for the vibrating stylus of the unit.

It is a further object of the invention to provide a vibrating stylus adapted for dependent adjustment of the pressure of the 10 stylus against the sound responsive medium and the spacing of the vibrator bar of the stylus with relation to the operating coils of the unit.

15 The invention will be readily understood from the following description of the accompanying drawing in which:

Fig. 1 is a vertical section through the improved unit.

20 Fig. 2 is a front elevation of the unit with the casing removed.

Fig. 3 is a transverse section on the line 3—3 of Fig. 1.

25 Fig. 4 is a side elevation of the unit showing a modified form of the invention.

Fig. 5 is a detail section on the line 5—5 of Fig. 4.

30 Fig. 6 is a side elevation of the unit showing a still further modification of the mounting for the same.

The improved operating unit is of general utility for vibrating a sound responsive medium, and may be employed in connection with a sound reproducer such as set forth 35 in my co-pending application, Ser. No. 57,153, filed Sept. 18, 1925. In this embodiment of the invention the unit directly vibrates a sounding board so as to eliminate the necessity for a diaphragm, and it is for 40 such a specific construction that the unit is particularly adapted.

The sounding board may be mounted on a suitable support 1, and may comprise boards 2^b at opposite sides of the support as 45 shown in Fig. 6 or may comprise board 2 at one side only of the support as shown in Fig. 1; or a sounding board may be mounted on the underside of the base 1^a of a radio cabinet A as shown in Fig. 4. The sounding board is preferably curved with its edges secured to its support as shown at 3, and its medial portion spaced from the support to form an air pocket 4.

The operating unit is mounted on a base 5 which supports a casing 40 enclosing the mechanism, in the form of the invention shown in Figs. 1 and 4, the unit is cushioned relative to the sounding board. As an instance of this arrangement a block 6 of yieldable cushioning material such as rubber is interposed between one end of the unit and its support, with a bolt 7 received through the support, the cushioning block, and the fixed end of the unit; and the opposite end of the unit is free for slight swinging movement by yielding of the cushioning block. In the front of the invention illustrated in Fig. 6 the unit is fixed relative to the support by an interposed non-yielding block 6^b and a bolt 7^b.

70 The operating unit includes a bar 12 mounted for vibration by electric impulses in usual manner, the actuating mechanism being shown as of standard type employed in radio reception and comprising a laminated bar 8 on the base 5, with coils 9 mounted thereon and a permanent horseshoe magnet 10 surrounding the coils. The bar 12 is yieldably spaced from coils 9 for vibration of the bar in accordance with impulses 75 transmitted to the coils through wires 13 which lead to a radio receiving set or other source of electrical impulses.

75 The mounting for bar 12 comprises screws 14 threaded through base 5 and provided with lock nuts 15, with the ends of the screws projecting beyond coils 9 and forming points 16 on which an end of the bar 12 is supported. An adjusting screw 17 extends through bar 12 between the screws 14 and is threaded into the base 5; and the adjusting screw has a flexible washer 18 and a coil spring 19 between its head and the bar 12 in order to press the end of the bar 90 against its pointed supports.

95 The opposite end of bar 12 overlies the coils 9 and is yieldably held in spaced relation therefrom by a leaf spring 20 fixed to the bar and having a projecting end which is mounted on a screw 21 carried by the base 5. The end of the leaf spring is adjustably fixed on screw 21 by means of nuts 22 threaded on the screw against opposite faces of the spring.

100 One end of the bar 12 is thus yieldably held against points 16 by the spring 19, and

the opposite end of the bar being yieldably supported by spring 20, the coils 9 cooperate with the permanent magnet 10 to produce vibrations of the bar; and a stylus projects 5 perpendicularly from the vibrator bar and engages the sounding board of the device to correspondingly vibrate the sounding board and thereby produce and amplify the sound.

The bar 12 and the stylus form a structure 10 which in itself is comparatively rigid, but is adapted for vibration between the end supports 16 and 20, and the stylus is spaced between said end supports so that relative adjustment between the entire operating unit 15 and the sounding board will adjust the pressure of the stylus against the sounding board and will also adjust the spacing of bar 12 relative to coils 9.

In practice the stylus may be of any suitable 20 material depending upon the volume and quality of tone which is desired, and the position of the stylus on the vibrator bar with relation to the supports 16 is also determined in accordance with the tone which 25 it is desired to produce.

In the form of the invention illustrated in Figs. 1 and 6 the base 5 engages the block interposed between the unit and its support; and the stylus 25 projects from the side of 30 the vibrator bar which is away from coils 9, and extends through the casing 40 for engagement with the sounding board. As a consequence the pressure of the stylus is against the sounding board when the vibrator bar 12 returns to normal spaced relation from the coils during the intervals between 35 energizing thereof.

As illustrated in Fig. 4, the position of the operating unit is reversed so that casing 40 40 abuts against the cushioning block 6; and the stylus 25^a projects from the side of the vibrator bar which is toward coils 9, and extends through the base 5 for engagement with the sounding board 2^a, so that pressure 45 of the stylus is against the sounding board when the vibrating bar is drawn toward the coils 9 by the energizing of the latter.

The stylus of the unit may simply abut 50 against the sounding board as shown in Fig. 4, or it may extend through the sounding board and be fixed relative thereto by the nuts 26 as shown in Figs. 1 and 6.

The block between the support and the operating unit on which the unit is mounted 55 is preferably arranged so that the stylus of the unit is a radius of the curve of the sounding board in order that maximum vibration may be obtained; and for this purpose the block 6 is provided with an inclined contact 60 surface 27 against which the unit abuts.

The cushioning block 6 employed in the form of the inventions illustrated in Figs. 1 and 4, normally positions the operating unit 65 so that the pressure of the stylus against the sounding board is released; and the means

for swinging the operating unit from normal position by yielding of the cushioning block, in order to adjust the pressure of the stylus against the sounding board and at the same time adjust the spacing between vibrator bar 70 12 and coils 9, preferably comprises an operating cam 30 cooperating with the unit. The cam may be journaled in bearings 31 on the support 1, so as to press against the unit when the cam shaft 32 is turned; and the cam shaft is arranged for convenient turning 75 and automatic locking in adjusted position, by means of a manually operated key 33 which projects to the exterior of the sounding board and has a worm driving connection 34 for the cam shaft.

In the form of the invention illustrated in Fig. 6, where the operating unit is rigidly fixed relative to support 1 by means of the non-yielding block 6^a, the pressure of the 85 stylus against the sounding board and the spacing of the vibrator bar relative to the coils, is regulated by adjustment of the sounding board relative to the stylus which is fixed thereto. As an instance of this arrangement an operating rod 50 which is adapted for manual turning, may be axially fixed relative to the sounding board by means of collars 51, and axially adjustable relative to the support 1 by means of the 90 threaded connection 52.

I claim:

1. A sound reproducer comprising a support, a sounding board fixed at its edges to the support with its medial portion spaced from the support, an electro-magnetic actuating means on the support, a vibrator, a mounting for the vibrator positioning it in normal spaced relation from the actuating means, means for tensioning said mounting to yieldably retain the vibrator in normal position against movement toward or away from the actuating means, a stylus on the vibrator engaging the sounding board, and means for dependently adjusting the pressure of the stylus relative to the sounding board and the normal spacing of the vibrator from the actuating means. 100

2. A sound reproducer comprising a support; an operating unit mounted on the support; a sound responsive medium mounted on the support in spaced relation from the operating unit; said operating unit comprising an electro-magnetic actuating means, a vibrator, a mounting for the vibrator positioning it in normal spaced relation from the actuating means, means for tensioning said mounting to yieldably retain the vibrator in normal position against movement toward or away from the actuating means, and a stylus 115 on the vibrator engaging the sound responsive medium; and means for adjusting the spacing between the sound responsive medium and the operating unit and thereby 120 dependently adjust the pressure of the stylus 125 130

relative to the sound responsive medium and the normal spacing of the vibrator from the actuating means.

3. An operating unit for a sound responsive medium comprising electro-magnetic actuating means, a vibrator, mountings for opposite ends of the vibrator positioning it in normal spaced relation from the actuating means, means for tensioning the mountings
- 5 at said opposite ends of the vibrator to yieldably retain the vibrator in normal position against movement toward or away from the actuating means, and a stylus on the vibrator adapted to engage the sound responsive medium.
- 10 4. An operating unit for a sound responsive medium comprising electro-magnetic actuating means, an inherently rigid vibrator and stylus, a mounting for the vibrator positioning it in normal spaced relation from the actuating means with the stylus engaging the sound responsive medium, said mounting comprising a tensioned pivotal support on the operating unit for one end of the vibrator
- 15
- 20

and a leaf spring carried by the operating unit and fixed to the other end of the vibrator, and means for adjusting the relative position of the operating unit and the sound responsive medium so as to dependently adjust the pressure of the stylus relative to the sound responsive medium and the normal spacing of the vibrator from the actuating means.

5. An operating unit for a sound responsive medium comprising electro-magnetic actuating means, an inherently rigid vibrator and stylus, and a mounting positioning the vibrator in normal spaced relation from the actuating means with the stylus engaging the sound responsive medium, said mounting comprising a pivotal support for one end of the vibrator and a leaf spring support for its opposite end whereby the vibrator is tensioned in normal position against movement toward or away from the actuating means.

In testimony whereof he has affixed his signature to this specification.

GEORGE C. LINDSEY.
